UNITED STATES PATENT OFFICE.

JOSEPHINE M. SPIELBAUER, OF SEATTLE, WASHINGTON.

CAP-REMOVER.

1,116,509.

Specification of Letters Patent.

Patented Nov. 10, 1914.

Original application filed March 5, 1913, Serial No. 752,185. Divided and this application filed September 15, 1913. Serial No. 789,933.

To all whom it may concern:

Be it known that I, JOSEPHINE M. SPIELBAUER, a citizen of the United States, residing at Seattle, in the county of King and State of Washington, have invented certain new and useful Improvements in Cap-Removers, of which the following is a specification, reference being had to the accompanying drawings.

10 This invention relates to new and useful improvements in cap removers and the object of the invention is to provide a device of this general character having novel and improved means whereby the same may be readily and conveniently adjusted into folded position so that the same may be conveniently carried in a pocket or the like.

The invention consists in the details of construction and in the combination and arrangement of the several parts whereby certain important advantages are attained and the device is rendered simpler, less expensive and otherwise more convenient and advantageous for use, all as will be hereinafter 25 more fully set forth.

The novel features of the invention will be carefully defined in the appended claim.

In order that my invention may be the better understood, I will now proceed to 30 describe the same with reference to the accompanying drawings, wherein—

Figure 1 is a view in front elevation of a cap remover constructed in accordance with my invention, and adjusted into folded position; Fig. 2 is a view in side elevation of the device as shown in Fig. 1; and Fig. 3 is a sectional view taken on the line 3—3 of Fig. 1, but with the lever member shown 40 adjusted into its limit of outward movement.

As disclosed in the accompanying drawings, 1 denotes a loop member, the ends 2—2 of which are flattened with their transverse diameters substantially perpendicular to the 45 transverse diameter of the loop proper and extend outwardly from the loop in spaced parallel relation and each having their free ends disposed on a bevel, as indicated at 3, as and for a purpose to be more particularly 50 referred to.

The loop member 1 is adapted to be applied to a bottle cap preferably of the crimped type, while the under edge of such cap is adapted to be engaged by the projection 4 extending forwardly substantially at

the center of one side portion of an end of the elongated member 5, the portion of such member 5 adjacent the projection 4 being snugly accommodated between the spaced ends 2—2 and pivotally supported therebetween through the medium of the transversely directed pin 7 extended through the end portions 2—2 adjacent the inner ends thereof and through the elongated member 5. The portion of the elongated member 5 positioned between the end portions 2 is of such a thickness that, when the parts are adjusted in operative position, the projection 4 will be slightly offset relatively to the loop 1. 60

The loop member 1 or more particularly the main portion thereof is formed of flattened material and adjacent the spaced ends 2, the transverse diameter of the wall of such loop is substantially equal to the distance from the pivotal pin 7 to the end of the elongated member 5 so that when the elongated member 5 is adjusted into a position with the projection 4 extending inwardly of the loop the inner end of such 65 elongated member 5 will be substantially flush with the inner walls of the loop member 1 so that no obstruction or hindrance will be offered to the projection 4 which would otherwise tend to interfere with the proper 70 engagement of such projection with the lower edge portion of the cap. 75

The elongated member 5 may be of any predetermined length and such member 5 is adapted to afford the requisite leverage 80 whereby the cap may be forced from operative position, and as herein disclosed this member 5 is provided with the oppositely disposed laterally directed lugs 8—8 adapted to contact with or abut the beveled ends 3 85 of the spaced parallel end portions 2 when such member 5 is adjusted to extend the projection 4 within the looped member 1, and for this reason the contacting edge surfaces 9 of the lugs 8 are beveled correspondingly 90 with the ends 3—3 whereby it will be obvious that when the parts are properly adjusted to remove the cap the bevels 3 and 9 will cause the parts to coöperate in the same manner as if they were integrally produced. 95

The greater end portion of the elongated member 5 may be for purposes of convenience formed into any requisite tool or implement. For convenience of illustration, I herein show such portion 10 formed as a 100

110

corkscrew, although it is obvious that it may be constructed to serve as a nail file, button hook or the like, and in order to serve as a protection for the extremities of this portion 10 when in folded position relatively to the loop 1, I provide such loop 1 diametrically opposite to the end portions 2 with the elongated extension 11 provided with the inwardly directed open ended recess 12 into which the free end portion of such part 10 is adapted to extend as is thought to be clearly obvious. Also for the purposes of convenience, the free end portion of the extension 11 may be sharpened, as indicated at 15 14, to serve as a screw-driver while the intermediate portion of the extension may be provided with a substantially rectangular opening 15 whereby the device may serve as a manipulating device, such, for instance, 20 as a presto-light key.

From the foregoing description of my improvements, it is thought to be obvious that a cap remover constructed in accordance with my invention is of an extremely simple 25 and comparatively inexpensive nature and is particularly well adapted for use by reason of the convenience and facility with which it may be adjusted either into folded or extended position and by reason of the effectiveness with which the adjusted parts cooperate in order to create the necessary leverage and it will also be obvious that a cap remover constructed in accordance with my invention is susceptible of some change and 30 modification without material departure from the principles and scope thereof and for this reason I do not wish to be understood as limiting myself to the precise arrangement and formation of the several parts, herein 35 shown, in carrying out my invention in 40 practice.

I claim:

In combination, a flat looped member adapted to overlie a cap to be removed and having its end portions disposed outwardly 45 in parallel relation, the transverse diameters of such end portions being substantially perpendicular to the transverse diameter of the loop proper, the free extremities of such end portions being beveled, an elongated member 50 pivotally supported adjacent one of its extremities between the end portions of the loop, a longitudinally disposed projection arranged at the free end of the short member of the elongated member and offset relative to the looped member and adapted to engage the marginal portion of the cap when the elongated member is adjusted with its longer arm directed outwardly, oppositely disposed laterally directed lugs carried by 55 the long arm of the elongated member in such proximity to the pivot thereof as to contact with the extremities of the looped member when the longer arm is adjusted outwardly from the looped member, the contacting surfaces of such lugs being correspondingly beveled whereby the movement of the elongated member about its pivot is limited in one direction, such looped member at a point diametrically opposite its spaced 60 extremities being provided with an elongated extension provided with an inwardly directed open ended recess to accommodate the free end of the long arm of the elongated member when such long arm is folded in a 65 position to extend across the looped member.

In testimony whereof I hereunto affix my signature in the presence of two witnesses:

JOSEPHINE M. SPIELBAUER.
